UNITED STATES PATENT OFFICE.

RUSSELL D. BELDEN, OF BUFFALO, NEW YORK, ASSIGNOR TO MADISON TIRE & RUBBER COMPANY, INC., OF BUFFALO, NEW YORK, A CORPORATION OF NEW YORK.

DESIGN FOR A TIRE CASING.

Application filed January 16, 1922. Serial No. 211. Term of patent 3½ years.

To all whom it may concern:

Be it known that I, RUSSELL D. BELDEN, a citizen of the United States, residing at Buffalo, in the county of Erie and State of New York, have invented a new, original, and ornamental Design for Tire Casings, of which the following is a specification, reference being had to the accompanying drawing, forming part thereof.

In the drawings,—

Figure 1 is a plan view of a section of the

tread of a tire embodying the features of the present invention.

Figure 2 is a transverse section therethrough.

I claim:—

The ornamental design for a tire casing, as shown.

RUSSELL D. BELDEN.
